UNITED STATES PATENT OFFICE

120,255

DESIGN FOR A DINNER BELL

Hamilton O. Cornwall, Pelham Manor, N. Y.

Application January 27, 1940, Serial No. 89,795

Term of patent 3½ years

To all whom it may concern:

Be it known that I, Hamilton O. Cornwall, a citizen of the United States and residing at Pelham Manor, in the county of Westchester and State of New York, have invented a new, original, and ornamental Design for a Dinner Bell, of which the following is a specification, reference being had to the accompanying drawing, forming part thereof, and showing a perspective view of the dinner bell embodying my new design.

I claim:

The ornamental design for a dinner bell, substantially as shown.

HAMILTON O. CORNWALL.
